CLAIM

The ornamental design for a cylinder cart with lowering lever, as shown and described.

DESCRIPTION

FIG. 1 is a perspective view of the cylinder cart with lowering lever showing my new design;

FIG. 2 is a front elevational view thereof;

FIG. 3 is a right side elevational view thereof with the left side elevational view being a mirror image thereof;

FIG. 4 is a rear elevational view thereof;

FIG. 5 is a top plan view thereof; and,

FIG. 6 is a bottom plan view thereof.
